CLAIM

The ornamental design for the multipurpose forceps as shown and described.

DESCRIPTION

FIG. 1 is a front perspective view of an embodiment of a multipurpose forceps, in accordance with the disclosed principles;

FIG. 2 is a front elevation view of the multipurpose forceps illustrated in FIG. 1;

FIG. 3 is a rear elevation view of the multipurpose forceps illustrated in FIG. 1;

FIG. 4 is a right side view of the multipurpose forceps illustrated in FIG. 1;

FIG. 5 is a left side view of the multipurpose forceps illustrated in FIG. 1;

FIG. 6 is a top view of the multipurpose forceps illustrated in FIG. 1;

FIG. 7 is a bottom view of the multipurpose forceps illustrated in FIG. 1;

FIG. 8 is a rear perspective view of the multipurpose forceps illustrated in FIG. 1;

FIG. 9 is a detail view of a portion of the multipurpose forceps illustrated in FIG. 1; and,

FIG. 10 is a detail view of a portion of the multipurpose forceps illustrated in FIG. 1.

Broken lines illustrated as dash-dot-dash are boundary lines in the drawings that separate claimed areas and disclaimed areas of the multipurpose forceps, while broken lines illustrated as dash-dash-dot are phantom lines in the drawings that depict disclaimed portions of the multipurpose forceps that form no part of the claimed design.

1 Claim, 8 Drawing Sheets
